FREQUENCY CONVERTER

Marcel A. Lissman, Cambridge, Mass., assignor to
Raytheon Manufacturing Company, Newton,
Mass., a corporation of Delaware

Application May 9, 1946, Serial No. 668,607

4 Claims. (Cl. 250—36)

1

This invention relates to frequency converters, and more particularly to aperiodic frequency converters especially suitable for transforming commercial power supply frequencies to higher frequencies.

While not limited thereto, the present invention is admirably adapted for generating directly from the raw alternating current of commercial power lines the high-frequency power utilized in induction or dielectric heating.

Apparatus of the type to which the present invention relates generally comprises a plurality of oscillatory circuits having a single frequency-determining network in common resonant to the frequency desired of the output of the device, said oscillatory circuits including high-vacuum electron-discharge devices which, when suitably energized and commutated, for example, from a multi-phase commercial power source, permit their respective oscillatory circuits successively to function, whereby said frequency-determining network is continuously excited at the aforesaid resonant frequency.

Existing systems of the character just described have the disadvantage of being unable to withstand the inverse voltages applied to their electron-discharge devices during the negative alternations of the various phases of their power supplies, said inverse voltages causing said electron-discharge devices to become damaged.

It is, therefore, the main object of the present invention to design the energizing circuits of the electron-discharge devices of converter systems of the type to which the present invention relates so as to protect said electron-discharge devices against the above referred to damage.

This, and other objects of the present invention, which will become more apparent as the detailed description thereof progresses, are attained, briefly, in the following manner:

The invention conventionally contemplates the provision of a plurality of oscillatory circuits having a single frequency-determining network in common, said frequency-determining network being resonant to the frequency desired of the output of the device. Each such oscillatory circuit includes a high-vacuum electron-discharge device for controlling the operation thereof. Energy is applied to said oscillatory circuits from a commercial multi-phase power source, the number of said oscillatory circuits corresponding to the number of phases of said power source. For the purposes of this specification, the invention will be described in connection with a 3-phase power source.

2

The electron-discharge devices are so successively energized and commutated that the oscillatory circuit whose electron-discharge device instantaneously has the most positive potential applied to the anode thereof controls the high-frequency oscillations. As a result, said oscillatory circuits are successively brought into operation to cause the above referred to common frequency-determining network to be continuously excited. Inasmuch as each electron-discharge device conducts for only one-third of the time, greater heat dissipation is permissible, and greater output power is therefore obtainable.

The oscillatory circuits are self-biasing, and a single means, common to all of said oscillatory circuits, is utilized to obtain said bias, thereby materially reducing the control electrode current which flows from that associated with commutating methods previously employed.

Preferably, said oscillatory circuits are of the tuned-plate, tuned-grid type, with the commutating voltage so introduced into a grounded control electrode circuit that it is effectively in series with the anode voltage, whereby the anode-cathode voltage consists of the sum of the voltages applied between the grounded control electrode and anode, and the grounded control electrode and cathode. By means of such an arrangement, the commutating voltage contributes to the power output of the device.

In order to protect the electron-discharge devices of the various oscillatory circuits against the inverse voltages of the multi-phases of the power supply, the anodes of said electron-discharge devices are so returned to ground, through non-linear impedances, for example, gaseous-discharge tubes, that at no time can any of said anodes become negative with respect to their corresponding cathodes.

In the accompanying specification there shall be described, and in the annexed drawing shown, an illustrative embodiment of the frequency converter of the present invention. It is, however, to be clearly understood that the present invention is not to be limited to the details herein shown and described for purposes of illustration only, inasmuch as changes therein may be made without the exercise of invention, and within the true spirit and scope of the claims hereto appended.

In said drawing,

Fig. 1 is a circuit diagram of an aperiodic frequency converter assembled in accordance with the principles of the present invention; and

Fig. 2 shows the relationship of the voltages of

the three-phase power supply utilized in connection with the circuit of Fig. 1.

Referring now more in detail to the aforesaid illustrative embodiment of the present invention, with particular reference to Fig. 1 of the drawing, the numerals 10, 11 and 12 generally designate high-vacuum electron-discharge devices including, respectively, cathodes 13, 14 and 15, anodes 16, 17 and 18, and control electrodes 19, 20 and 21.

The cathodes 13, 14 and 15 of the electron-discharge devices 10, 11 and 12 are connected, respectively, through star-connected secondary windings 22, 23 and 24 of a three-phase power transformer 25, to ground, as at 26, and, respectively, through radio-frequency by-pass capacitors 27, 28 and 29, to ground, as at 30. Said transformer additionally includes primary windings 31, 32 and 33 connected to the lines 34, 35 and 36 of a three-phase power source, and also another group of secondary windings 37, 38 and 39 which are star-connected, as at 39', and so disposed with respect to the secondary windings 22, 23 and 24 as to be 180° out of phase, respectively, therewith. The outer terminals of the windings 37, 38 and 39 are connected, respectively, to the anodes 16, 17 and 18 of the electron-discharge devices 10, 11 and 12, the conductors connecting said windings to said anodes being, preferably, threaded through a hollow, coiled conductor 40, one end of which is grounded, as at 41, and the other end of which is connected to one of the plates of a capacitor 42. By so threading the connections between the windings and anodes, the necessity for radio-frequency chokes is eliminated. The remaining plate of the capacitor 42 is grounded, as at 43, said capacitor 42 and said coiled conductor 40 constituting a tank circuit resonant to the frequency desired of the output of the device. Said tank circuit is coupled to the anodes 16, 17 and 18 of the electron-discharge devices 10, 11 and 12, respectively, through capacitors 44, 45 and 46. When the device is employed for dielectric heating, the plates of the capacitor 42 may receive a load 47 therebetween.

The control electrodes 19, 20 and 21 of the electron-discharge devices 10, 11 and 12 are all connected to ground, as at 48, through an inductor 49 and capacitor 50, the latter being shunted by a potentiometer 51.

There is thus presented an aperiodic frequency converter which is designed to operate from a multi-phase commercial power source, and which comprises a plurality of tuned-plate, tuned-grid oscillatory circuits having a single frequency-determining network in common, said oscillatory circuits being successively operable, as will hereinafter be described, to continuously excite said frequency-determining network at the above referred to output frequency of the device.

It will be noted, however, that the electron-discharge devices 10, 11 and 12 are successively subjected to high inverse voltages, and in order to protect them against damage, the outer terminals of the star-connected secondary windings 37, 38 and 39 are connected, respectively, to the cathodes 52, 53 and 54 of gaseous-discharge tubes 55, 56 and 57, said tubes including anodes 58, 59 and 60, all of which are connected to ground, as at 61.

In Fig. 2 of the drawing, there are shown three voltages A, B and C, corresponding to the three phases, spaced 120° apart, of the commercial power lines 34, 35 and 36. The voltages induced in the secondary windings 37, 38 and 39 are in phase opposition, respectively, to the voltages in-

duced in the secondary windings 22, 23 and 24, but the former are intended to be of considerably greater magnitude than the latter.

It will be assumed, for the purposes of this specification, that the peak voltage across each secondary winding 37, 38 and 39 is 4500 volts; that the peak voltage across each secondary winding 22, 23 and 24 is 500 volts; and that the peak radio-frequency drive on the control electrodes 10, 19, 20 and 21 of the electron-discharge devices 10, 11 and 12 is 500 volts.

Now, the method of commutating the oscillatory circuits of the present invention is such that the electron-discharge device having the instantaneously most positive potential applied to its anode controls the high-frequency oscillations of the device, the conducting state of said last-named electron-discharge device adjusting the bias applied to each of the electron-discharge devices in a manner similar to conventional self-biasing oscillators having direct-current power supplies. In other words, as each electron-discharge device becomes conducting, such control electrode rectification occurs therein as to maintain the remaining electron-discharge devices in a non-conducting state, with such a negative potential on the control electrodes of said last-named electron-discharge devices that substantially no control electrode rectification can take place therein.

Consider the time t_1 , indicated in Fig. 2 of the drawing, at which the voltage across the winding 37, corresponding to phase A, is somewhat greater than one-half its positive peak, for example, 2300 volts; the voltage across the winding 38, corresponding to phase B, is somewhat less than its negative peak, for example, 4450 volts; and the voltage across the winding 39, corresponding to phase C, is somewhat less than one-half its positive peak, for example, 2200 volts, all with respect to the floating neutral point 39', which will be considered a reference point.

Under these circumstances, the cathode 52 of the gaseous-discharge tube 55 will be positive with respect to the anode 58 of said tube, and said tube will be non-conducting. The cathode 54 of the gaseous-discharge tube 57 will be positive with respect to the anode 60 of said tube, and said tube will also be non-conducting. However, the cathode 53 of the gaseous-discharge tube 56 will be negative with respect to the anode 59 of said tube, and said tube will be conducting.

Hence, there appears upon the anode 16 of the electron-discharge device 10 a voltage which is 6750 volts positive (the sum of the voltages across the windings 37 and 38) with respect to the grounded control electrode 19 of said electron-discharge device, and the latter, assuming, as will later be described, that its control electrode is at a suitable potential with respect to its cathode, will be conducting.

There appears upon the anode 18 of the electron-discharge device 12 a voltage which is 6650 volts positive (the sum of the voltages across the windings 38 and 39) with respect to the grounded control electrode 21 of said electron-discharge device, but, as will later be described, the potential on said control electrode is such with respect to the cathode 15 that said electron-discharge device is maintained non-conducting.

The anode 17 of the electron-discharge device 11 is, by reason of the conducting state of the gaseous-discharge tube 56, at the same potential as the grounded control electrode 20, and therefore, said electron-discharge device is protected

against the inverse voltage across the winding 38.

Now, consider the time t_2 , indicated in Fig. 2 of the drawing, at which the voltage across the winding 37, corresponding to phase A, is somewhat less than its positive peak, for example, 4450 volts; the voltage across the winding 38, corresponding to phase B, is somewhat less than one-half its negative peak, for example, 2200 volts; and the voltage across the winding 39, corresponding to phase C, is somewhat greater than one-half its negative peak, for example, 2300 volts, again, all with respect to the reference point 39'.

Under these circumstances, the cathode 52 of the gaseous-discharge tube 55 will still be positive with respect to the anode 58 of said tube, and said tube will still be non-conducting. The cathode 53 of the gaseous-discharge tube 56 will now be positive with respect to the anode 59 of said tube, and said tube will now be non-conducting. However, the cathode 54 of the gaseous-discharge tube 57 will now be negative with respect to the anode 60 of said tube, and said tube will now be conducting.

Hence, there still appears upon the anode 16 of the electron-discharge device 10 a voltage which is 6750 volts positive (the sum of the voltages across the windings 37 and 39) with respect to the grounded control electrode 19 of said electron-discharge device, and the latter, assuming that its control electrode is still at a suitable potential with respect to its cathode, will still be conducting.

There appears upon the anode 17 of the electron-discharge device 11 a voltage which is 100 volts positive (the sum of the voltages across the windings 38 and 39) with respect to the grounded control electrode 20 of said electron-discharge device, but the biasing potential on said control electrode is such with respect to the cathode 14 that said electron-discharge device is maintained non-conducting.

The anode 18 of the electron-discharge device 12 is, by reason of the conducting state of the gaseous-discharge tube 57, at the same potential as the grounded control electrode 21, and therefore, said electron-discharge device is protected against the inverse voltage across the winding 39.

Now, consider the time t_3 , indicated in Fig. 2 of the drawing, at which the voltage across the winding 37, corresponding to phase A, is somewhat less than one-half its positive peak, for example, 2200 volts; the voltage across the winding 38, corresponding to phase B, is somewhat greater than one-half its positive peak, for example, 2300 volts; and the voltage across the winding 39, corresponding to phase C, is somewhat less than its negative peak, for example, 4450 volts, all with respect to the reference point 39'.

Under these circumstances, the cathode 52 of the gaseous-discharge tube 55 will still be positive with respect to the anode 58 of said tube, and said tube will still be non-conducting. The cathode 53 of the gaseous-discharge tube 56 will still be positive with respect to the anode 59 of said tube, and said tube will still be non-conducting. The cathode 54 of the gaseous-discharge tube 57 will still be negative with respect to the anode 16 of said tube, and said tube will still be conducting.

Hence, there still appears upon the anode 16 of the electron-discharge device 10 a voltage which is 6650 volts positive (the sum of the voltages across the windings 37 and 39) with respect to the grounded control electrode 19 of said electron-discharge device, but the latter, assuming that its control electrode is at a suitable biasing

potential with respect to its cathode, will be non-conducting.

There appears upon the anode 17 of the electron-discharge device 11 a voltage which is 6750 volts positive (the sum of the voltages across the windings 38 and 39) with respect to the grounded control electrode 20 of said electron-discharge device, but it will be assumed that the potential on said control electrode is such with respect to the cathode 14 that said electron-discharge device is now conducting.

The anode 18 of the electron-discharge device 12 is, by reason of the conducting state of the gaseous-discharge tube 57, still at the same potential as the control electrode 21, and therefore, said electron-discharge device is still protected against the inverse voltage across the winding 39.

The cycle continues in such a manner that at time t_4 , the electron-discharge device 11 will still be conducting, the gaseous-discharge tube 55 will become conducting to protect the electron-discharge device 10 against the inverse voltage across the winding 37, the gaseous-discharge tube 56 will remain non-conducting, and the gaseous-discharge tube 57 will become non-conducting. At time t_5 , the electron-discharge device 12 will be conducting, the gaseous-discharge tube 55 will continue to conduct to protect the electron-discharge device 10, and the gaseous-discharge tubes 56 and 57 will remain non-conducting. At time t_6 , the electron-discharge device 12 will still be conducting, the gaseous-discharge tube 55 will no longer be conducting, the gaseous-discharge tube 56 will conduct to protect the electron-discharge device 11 against the inverse voltage across the winding 38, and the gaseous-discharge tube 57 will remain non-conducting.

Now, the commutating voltages across the windings 22, 23 and 24 will be explained.

Consider the time t_7 , indicated in Fig. 2 of the drawing, and assume that the peak voltages across the windings 37, 38 and 39 are 4500 volts, the peak voltages across the windings 22, 23 and 24 are 500 volts, and the radio-frequency drives on the control electrodes 19, 20 and 21 of the electron-discharge devices 10, 11 and 12 are 500 volts. Further assume that, with the above-mentioned radio-frequency drive applied to the control electrode 19 of the electron-discharge device 10, and without commutating voltage across the winding 22 being applied to said control electrode, the resistance value of the effective portion of the potentiometer 51 is such that, due to control electrode rectification in said electron-discharge device 10, there is a normal direct-current voltage drop across said effective portion of the potentiometer of 250 volts negative. Under the foregoing conditions, when, in addition to the radio-frequency drive, the commutating voltage of 500 volts is applied to the cathode 13 of the electron-discharge device 10, the control electrode thereof will have a positive excursion of 250 volts, and said last-named electron-discharge device will become conducting in phase with the power supply voltage A between the times t_8 and t_9 , provided the effective portion of the potentiometer 51 is increased to obtain an additional 500 volts direct-current drop thereacross. It will be noted that while the anode 16 of the electron-discharge device 10 is going positive with respect to the control electrode 19 thereof as a result of the voltage across the winding 37, the cathode 13 of said electron-discharge device 10 is going negative with respect to said control electrode 19 as a result of 75 the out-of-phase voltage across the secondary

winding 22. Thus, the anode-cathode voltage is the sum of the voltages across said windings 37 and 22, so that the commutating voltage actually contributes to the output power of the device.

It will also be noted that at the instant t_7 all control electrodes will be depressed 750 volts below ground potential, while the voltages across the secondary windings 23 and 24 will be 250 volts positive with respect to ground. As a result, biasing voltages will be applied to the control electrodes 20 and 21 of the electron-discharge devices 11 and 12 amounting to 1000 volts negative with respect to the cathodes 14 and 15 thereof. Hence, the latter two electron-discharge devices, when energized by the 500 volts radio-frequency drive, will still be biased 500 volts negative, more than enough to maintain them in a non-conducting state and prevent them from drawing control electrode current.

When the time t_8 is reached, commutation takes place, the electron-discharge device 11 takes over control of the circuit, and the devices 10 and 12 are maintained non-conducting. Finally, when the time t_{10} is reached, commutation again takes place, and between said time t_9 and time t_{11} , the electron-discharge device 12 conducts, and maintains the devices 10 and 11 in a non-conducting state.

While particular voltage values have been assumed in the foregoing explanation, it is to be clearly understood that these values are merely illustrative, and the components of the device may be adjusted to obtain any other values which will result in commutation of the character described. It is to be further understood that while tuned-plate, tuned-grid oscillators have been discussed herein, any other type of oscillator, or other electrical circuit, will function as well.

This completes the description of the aforesaid illustrative embodiment of the present invention. It will be noted from all of the foregoing that the present invention provides a simple and efficient device for converting commercial power frequencies to higher frequencies. It will further be noted that the device operates under conditions of efficiency, stability and regulation comparable to those of a conventional self-biasing oscillator having a direct-current power supply. It will be still further noted that control electrode rectification in the oscillation-controlling electron-discharge device alone controls the biasing of the remaining electron-discharge devices, and each electron-discharge device, during the periods that it is intended to be non-conducting, is protected against the inverse voltages of the various phases of the power supply.

Other objects and advantages of the present invention will readily occur to those skilled in the art to which the same relates.

What is claimed is:

1. In combination with an electrical circuit including a plurality of electron-discharge devices each of which has a cathode, a control electrode and an anode: means, adapted to be energized from a multiphase, alternating-current power supply, for applying such potential differences between the anodes and cathodes, and the control electrodes and cathodes of said electron-discharge devices as to render the same successively conducting; and a switching device connected across each of said electron-discharge devices, whereby the anodes of said electron-discharge devices are prevented from going negative with respect to

their corresponding cathodes during the negative alternations of said power-supply phases.

2. In combination with an electrical circuit including a plurality of electron-discharge devices each of which has a cathode, a control electrode and an anode: means, adapted to be energized from a multiphase, alternating-current power supply, for applying such potential differences between the anodes and cathodes, and the control electrodes and cathodes of said electron-discharge devices as to render the same successively conducting; and a gaseous-discharge tube inversely connected across each of said electron-discharge devices, whereby the anodes of said electron-discharge devices are prevented from going negative with respect to their corresponding cathodes during the negative alternations of said power-supply phases.

3. An aperiodic frequency converter comprising: a plurality of oscillatory circuits having a single frequency-determining network in common, said frequency-determining network being resonant to the frequency desired of the output of said converter; each of said oscillatory circuits including an electron-discharge device having a cathode, an anode, and a control electrode; means, adapted to be energized from a multiphase, alternating-current power supply of a frequency different than that desired of the output of said converter, for applying such potential differences between the anodes and cathodes, and the control electrodes and cathodes of said electron-discharge devices as to render the same successively conducting; and a switching device connected across each of said electron-discharge devices, whereby the anodes of said electron-discharge devices are prevented from going negative with respect to their corresponding cathodes during the negative alternations of said power-supply phases.

4. An aperiodic frequency converter comprising: a plurality of oscillatory circuits having a single frequency-determining network in common, said frequency-determining network being resonant to the frequency desired of the output of said converter; each of said oscillatory circuits including an electron-discharge device having a cathode, an anode, and a control electrode; means, adapted to be energized from a multiphase, alternating-current power supply of a frequency different than that desired of the output of said converter, for applying such potential differences between the anodes and cathodes, and the control electrodes and cathodes of said electron-discharge devices as to render the same successively conducting; and a gaseous-discharge tube inversely connected across each of said electron-discharge devices, whereby the anodes of said electron-discharge devices are prevented from going negative with respect to their corresponding cathodes during the negative alternations of said power-supply phases.
